CLAIM

The ornamental design for a self-cleaning pet grooming implement, as shown and described.

DESCRIPTION

1.1 is a front view of the self-cleaning pet grooming implement, wherein a brand logo is incorporated into the handle sub-assembly. The self-cleaning mechanism is at rest.

1.2 is a rear view of the self-cleaning pet grooming implement when the self-cleaning mechanism is at rest.

1.3 is a left side view of the self-cleaning pet grooming implement when the self-cleaning mechanism is at rest.

1.4 is a right side view of the self-cleaning pet grooming implement when the self-cleaning mechanism is at rest.

1.5 is a front left perspective view of the self-cleaning pet grooming implement when the self-cleaning mechanism is at rest.

1.6 is a rear right perspective view of the self-cleaning pet grooming implement when the self-cleaning mechanism is at rest, indicating the intended manner in which the implement is to be held.

1.7 is a front view, with the self-cleaning mechanism in the actuated position.

1.8 is a rear view of the self-cleaning pet grooming implement when the self-cleaning mechanism is in the actuated position.

(Continued)

1.9 is a left side view of the self-cleaning pet grooming implement when the self-cleaning mechanism is in the actuated position.

1.10 is a right side view of the self-cleaning pet grooming implement when the self-cleaning mechanism is in the actuated position.

1.11 is a front left perspective view of the self-cleaning pet grooming implement when the self-cleaning mechanism is in the actuated position.

1.12 is a rear left perspective view of the self-cleaning pet grooming implement when the self-cleaning mechanism is in the actuated position.

The broken lines shown are included for the purpose of illustrating portions of the self-cleaning pet grooming implement that form no part of the claim.
